RESONANT CIRCUIT

Dudley E. Foster, South Orange, N. J., assignor
to Radio Corporation of America, a corporation
of Delaware

Application May 7, 1941, Serial No. 392,313

9 Claims. (Cl. 250—40)

The present invention relates generally to radio frequency signalling apparatus and more particularly to improvements in circuits employing tuned circuits having iron core coils.

It is an object of the present invention to provide an arrangement for obtaining a constant resonant impedance over a wide range of radio frequencies in circuits employing iron core coils.

Another object of the invention is to formulate the relationship between the constants and characteristics of iron cores and coils to the end that uniform amplification is obtained in vacuum tube circuits over a very wide range of frequencies.

Additional objects of the invention will appear in the following detailed specification when read in connection with the appended drawing.

In the drawing:

Figure 1 is a sectional view of a coil and core assembly which will be referred to hereinafter in explaining the invention;

Figure 2 is a schematic wiring diagram illustrating one way in which a coil and core assembly constructed in accordance with the present invention may be incorporated in a radio frequency circuit; and,

Figure 3 is a curve sheet which will be referred to in explaining the invention. In Figure 3 there are shown curves of the loss factor per megacycle squared as a function of frequency for three different cores.

Referring more particularly to the drawing, Figure 1 illustrates a cylindrical coil 9 which is wound around a sleeve 14 of insulating material, and a core 10 mounted within sleeve 14. It is to be understood that the core 10 may be a ferro-magnetic core of the type usually employed in high frequency circuits. Suitable known cores for this purpose may be composed of comminuted iron or magnetite mixed with a binder and compressed or molded to the required shape.

In Figure 1, l_o is the length of the coil, b_i is the length of the core, b_o is the radius of the coil and b_i is the radius of the core. Another dimension of the coil which is found useful in certain equations to be herein discussed is the length of the coil diagonal which is given by the expression

$$\sqrt{4b_o^2 + l_o^2}$$

where b_o and l_o represent the coil radius and coil length respectively, as above set forth.

From electrical engineering theory, it is known that the inductance of a coil without iron core is given by the expression

$$L_o = \frac{4\pi^2 b_o^2 N^2}{\sqrt{4b_o^2 + l_o^2}}$$

where

L_o =inductance of the coil without a core

N =number of turns

The inductance of such a coil with an iron core is given by the expression

$$L_i = L_o \left(1 + \frac{b_i^2}{b_o^2} (\mu - 1) \right)$$

where

μ =effective permeability of core

L_i =inductance with the iron core

The power required to supply the coil losses is given by the expression

$$W = I^2 (R_o + R_i)$$

where

W =power required

I =the current through coil

R_o =resistance of coil without iron core

R_i =resistance added by the iron core

The core loss may also be expressed by

$$W_i = B_i^2 V_i \rho$$

where

W_i =power loss in the core

B_i =flux density in the core

V_i =volume of the core

ρ =specific loss factor for the iron core

Now

$$B_i = \frac{4\pi N I \mu}{\sqrt{4b_o^2 + l_o^2}}$$

so that the resistance added by the iron core may be stated to be

$$R_i = L_o \left(\frac{4\pi \mu^2 b_i^2 l_o \rho}{b_o^2 \sqrt{4b_o^2 + l_o^2}} \right)$$

The value of ρ derived from the expressions above varies greatly with frequency. If all the loss were due to eddy currents it would vary as the square of the frequency. In radio frequency applications it does vary approximately as the square of the frequency, particularly for frequencies above 8 or 10 mc., as may be seen from Figure 3. Consequently it is usually more convenient to express the loss factor as ρ per megacycle squared rather than directly.

The Q factor of a coil is given by the expression

$$Q = \frac{\omega L}{R}$$

where

$\omega = 2\pi$ times operating frequency

L =inductance

R =radio frequency resistance of the coil

In a coil employing iron

$$Q_i = \frac{\omega [L_o + L_o m(\mu - 1)]}{R_o + R_i}$$

where

$Q_i = Q$ of coil with iron

m = ratio

$$\frac{b_i^2}{b_o^2}$$

substituting the value of L_o above

$$Q_i = \frac{1 + m(\mu - 1)}{\frac{1}{Q_o} + \frac{1}{\omega} \frac{4\pi\mu^2\rho m \times 10^9}{\sqrt{1 + \left(\frac{2b_o}{l}\right)^2}}}$$

when dimensions are given in centimeters. Choosing the condition where the core substantially fills the coil, m becomes nearly equal to 1. If, in addition, we choose the dimensions of the coil so that

$$\sqrt{1 + \left(\frac{2b_o}{l}\right)^2} = 0.4\pi$$

which means that the diameter of the coil is approximately $\frac{3}{4}$ (more precisely 0.766 times) the length of the coil, and the core is equal to or greater in length than the coil, then

$$Q_i = \frac{\mu}{\frac{1}{Q_o} + \frac{\mu^2\rho \times 10^{10}}{\omega}}$$

which may also be written as

$$Q_i = \frac{\mu\omega Q_o}{\omega + Q_o\mu^2\beta}$$

where $\beta = \rho$ times 10^{10}

The term β is introduced for convenience and is referred to herein as the loss coefficient.

The multiplier of 10^{10} for ρ applies when dimensions are expressed in centimeters; resistance in ohms; inductances in henries and frequencies in cycles per second.

In Figure 2 is shown a tuned circuit in the plate of a vacuum tube comprising coil 9 with iron core 10, tuned by capacitance 11. The resonant impedance Z_i of the circuit between terminals 12 and 13 is, as is well known

$$Z_i = \omega L_i Q_i$$

where Z_i is resonant impedance of the circuit with the iron core coil. Substituting in this equation the values of L_i and Q_i

$$Z_i = \frac{\mu^2 Z_o \omega}{\omega + Q_o \mu^2 \beta}$$

where Z_o is resonant impedance of the circuit without iron core.

Now if the effective permeability μ of the core is larger than about $\sqrt{2}$, which is the case with all iron cores in use today as such cores have values of effective permeability ranging from 2 to upwards of 10 or 12, the first term of the denominator becomes much smaller than the second term and the tuned impedance is given closely by

$$Z_i = \frac{L_o}{\frac{\beta}{\omega^2}}$$

Now from the curves shown in Figure 3 it is seen that the specific loss factor per megacycle squared is substantially constant with frequency above 10 megacycles and for some irons above 6 megacycles. Therefore

$$\frac{\beta}{\omega^2}$$

is a constant in the high frequency range. Above 6 or 10 megacycles with practically all radio frequency iron in use today and with the coil and core proportions described above, the resonant impedance becomes independent of frequency.

It has been seen that

$$Q_i = \frac{\mu\omega Q_o}{\omega + Q_o\mu^2\rho \times 10^{10}}$$

10 when

$$\sqrt{1 + \left(\frac{2b_o}{l}\right)^2} = 0.4\pi$$

or

$$15 \quad \frac{\omega}{Q_i} = \frac{1}{Q_o} + \mu\rho \times 10^{10}$$

but

$$\frac{\omega}{Q}$$

20 is a measure of the selectivity of the circuit since

$$\frac{\omega}{Q} = \Delta\omega$$

25 where $\Delta\omega$ is 2π times the bandwidth of the response characteristic at 0.707 of maximum response, so

$$\Delta\omega_i = \frac{\Delta\omega_o}{\mu} + \mu\rho \times 10^{10}$$

30 where

$\Delta\omega_i = 2$ times bandwidth with iron

$\Delta\omega_o = 2\pi$ times bandwidth without iron.

35 In order for the bandwidth with iron to be less than the bandwidth without iron, that is in order for the iron core coil to have better selectivity than the coil without iron

$$40 \quad \frac{\mu^2\rho \times 10^{10}}{\mu - 1}$$

must be less than $\Delta\omega_o$. In the usual case with μ large

$$45 \quad \frac{\mu^2\rho \times 10^{10}}{\mu - 1}$$

is nearly equal to $\mu\rho$, in which case if $\mu\rho$ times 10^{10} is less than $\Delta\omega_o$ the selectivity is improved by use of iron. Now

$$50 \quad \Delta\omega_o = \frac{\omega_o}{Q_o} = \frac{R_o}{L_o}$$

so the product of $\mu\rho$ time 10^{10} must be less than the ratio of radio frequency resistance to inductance in order for the iron core to improve selectivity. The factor 10^{10} is used when coil dimensions are in centimeters and resistances are in ohms and in that sense is merely a proportionality factor.

Having thus described my invention, what I claim is:

60 1. In a radio frequency resonant circuit adapted to be tuned to frequencies above 6 megacycles, a coil, a magnetic core within said coil and occupying substantially all of the space within the coil, said core having an effective permeability μ and a loss coefficient β such that the product of μ and β is less than the ratio of the radio frequency resistance to the inductance of the coil with the core removed whereby the circuit impedance is substantially constant over a range of frequencies above 6 megacycles.

65 2. The arrangement described in claim 1 wherein the length of the coil is at least 1.3 times its diameter.

70 3. The arrangement described in claim 1

wherein the core is composed of comminuted magnetic material mixed with a binder said core having an effective permeability of over 1.4.

4. The arrangement described in claim 1 wherein the length of the coil is approximately 1.3 times its diameter and the core is composed of comminuted iron, the core having an effective permeability which is at least 1.4.

5. In a resonant circuit which presents a substantially constant impedance over a predetermined wide range of radio frequencies above 10 megacycles, a cylindrical inductance coil having a length which is at least 1.3 times its diameter and an iron core substantially filling the space within said coil, said core having an effective permeability greater than 1.4 and a loss coefficient which varies substantially as the square of the frequency.

6. In a high frequency resonant circuit having a resonant impedance which is substantially constant with respect to frequencies above a frequency of approximately 8 megacycles, an inductance comprising a cylindrical coil whose length is at least 1.3 times its diameter and a core substantially filling the space within said coil, said core having an effective permeability which is at least 1.4 and a ratio of loss coefficient to the square of the frequency which is substantially constant.

7. In an iron core coil adapted to be used in a resonant circuit tuned to frequencies above 8 megacycles, in which the core occupies substan-

tially all of the space within the coil, said core having an effective permeability μ and loss coefficient β such that the product of μ and β is less than the ratio of the radio frequency resistance to the inductance of the coil with the iron core removed.

8. In a resonant circuit, a cylindrical coil whose length is approximately 1.3 times its diameter, a magnetic core inserted fully within said coil and having a permeability greater than 1.5 and a substantially constant β/ω^2 above about 10 megacycles, where β is the specific loss factor of the core and ω is 2π times the operating frequency, said core having a diameter slightly smaller than the inside diameter of said coil and a length at least equal to the length of the coil.

9. In a resonant circuit adapted to be tuned to frequencies above 10 megacycles, an inductance coil having an iron core which occupies substantially all of the space within said coil, said coil having a length which is equal to or greater than 1.3 times its diameter, the impedance of said resonant circuit being substantially equal to

$$\frac{L_0}{\beta/\omega^2}$$

and being substantially constant for frequencies above 10 megacycles where L_0 is the inductance of the coil without iron and β is the specific loss factor of the iron core.
